CLAIM

The ornamental design for a fragrance machine, as shown.

DESCRIPTION

FIG. 1 is a front view of a fragrance machine showing our new design;

FIG. 2 is a rear view thereof;

FIG. 3 is a side view thereof;

FIG. 4 is a top view thereof;

FIG. 5 is a bottom view thereof; and,

FIG. 6 is a perspective view thereof.

The portions of the article shown in broken lines form no part of the claimed design.
